US00D991416S

(12) **United States Design Patent** (10) **Patent No.:** **US D991,416 S**
(45) **Date of Patent:** **** Jul. 4, 2023**

(54) **THREADED CONNECTION PIPE**

(71) Applicant: **Jiangsu Mingqian Intellectual Property Co., Ltd.**, Wuxi (CN)

(72) Inventor: **Guoqing Lu**, Wuxi (CN)

(73) Assignee: **Jiangsu Mingqian Intellectual Property Co., Ltd.**, Wuxi (CN)

(**) Term: **15 Years**

(21) Appl. No.: **29/844,000**

(22) Filed: **Jun. 25, 2022**

(51) **LOC (14) Cl.** **23-01**

(52) **U.S. Cl.**

USPC **D23/266**; D23/262

(58) **Field of Classification Search**

(57) **CLAIM**

The ornamental design for a threaded connection pipe, as shown and described.

DESCRIPTION

FIG. 1 is a bottom perspective view of a threaded connection pipe, showing my new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is top perspective view thereof.
